GARMENT PRESSING MACHINE

Thomas Yosyk, Ridgewood, N. Y.

Application August 2, 1935, Serial No. 34,439

4 Claims. (Cl. 38—36)

My present invention relates to garment pressing machines, and particularly to improvements in manually operable pressing machines.

The objects of my invention include the provision of a relatively short hand operated lever located conveniently to the operator and movable with light effort to close the press under great pressure; and the provision of both a hand and foot lever selectively and collectively operable to close the press under great pressure with relatively light effort.

The foregoing and other objects and advantages of the invention will become more apparent and will be pointed out during the course of the following detailed description of the accompanying drawings, in which:

Fig. 1 is a side elevation partly in section of a garment pressing machine embodying one form of my invention and showing the press open;

Fig. 2 is a view similar to Fig. 1, showing the press closed;

Fig. 3 is a view taken on the line 3—3 of Fig. 2; and

Fig. 4 is a view similar to Fig. 1, showing the combined hand and foot levers.

Referring to the drawings, the letter B designates the buck or fixed pressing element which is mounted on the frame F above the usual table T, and the letter H designates the head or movable pressing element connected to the forward end of the lever L, which is fulcrumed at 8 on the extension 9 of the frame. The rear end of lever L is provided with a counterweight W. The numeral 10 designates generally a connection between the lever L and the main or rear toggle presently described. The construction, arrangement, and function of the connection 10 is disclosed in detail in my Patent No. 1,992,342 of February 26, 1935.

The lower member of the connection 10 is pivotally connected at 11 to the upper link 12 of the main or rear toggle, which link is pivotally connected at 13 to the lower long links 14, which are fulcrumed at 15 on the frame F. Coil springs 16 are connected at one end to studs 17 on the links 14, and at their outer ends to pin or shaft 18 secured between brackets or wings 19 formed as a part of or secured to the front 20 of the frame. The springs 16 normally tend to pull the links 14 toward the front of the frame to break or flex the toggle 12—14.

A second toggle comprising the links 21—22, pivotally connected at 23, is operatively connected to the links 14 of the main or rear toggle

by a pivotal connection 24 between the links 14. The forward end of the link 21 is pivoted on the shaft or stud 18. The link 21 may, if desired, be provided with extensions 25 receiving screws 26 to adjust pads 27 with respect to the links 32 so as to afford a cushioning effect between the links 21 and 22 when the press is being closed, and to adjust the relative position of the said links at the closed position of the press, that is, to permit the said links to be thrown past dead-center to lock the press closed, or not to pass dead-center to prevent locking of the press in its closed position.

If desired, the links 22 may be extended beyond the links 14 as by providing extensions 28 having therein slots 29 to receive bolts 30 which extend thru a weight 31 and thru the slots 29 to adjustably secure the weight 31 on the extension 28. In the embodiment of the invention being described, the weight will descend during closing movement of the press as may be readily seen by comparing the positions of Figs. 1 and 2. This descending movement of the weight assists in the closing of the press and lessens the amount of force required on the operating lever to close the press, and also when the press is opened the ascending movement of the weight 31 retards the opening movement to an extent which prevents an abrupt shock.

A third toggle is composed of the links 32 and 33 pivotally connected at 34. The link 32 is fulcrumed at 35 on the base of the frame and the link 33 is connected to the shaft 23 which connects links 21—22 of the second toggle.

A bell-crank lever 36 is fulcrumed on a shaft 37 between the brackets or wings 19 adjacent the front of the frame, and has its long arm 38 pivotally connected at 39 to an adjustable link 40 also connected to the shaft or pin 34, which connects links 32 and 33. The short arm 41 of the bell-crank 36 is pivotally connected at 42 to a link 43, which is pivotally connected at 44 to the short curved end or arm 45 of a hand operated lever, which is pivoted at 46 between the brackets 19. The relatively long straight arm 47 of the hand lever extends thru an opening 48 in the front of the frame, and is provided with a handle 49 on its outer end to be gripped by the operator when moving the lever in opening and closing the press. It will be noted that the hand lever is mounted adjacent the work table T convenient to the hand of the operator. It will also be noted that the arm 47 of the hand lever is relatively long, while the arm 46 is relatively short, so that 55

by a minimum effort the lever is moved on its fulcrum 46 to actuate the toggles and other parts of the machine in opening and closing the same.

Referring to Fig. 1, where the press is shown in open position, it will be noted that the arm 47 and handle 49 of the hand lever are in elevated position, at which time the arm 38 of the bell crank is lowered and the toggles are broken. To close the press, that is, to establish the parts in the position of Fig. 2, it is simply necessary to push down on the arm 47 of the hand lever which causes the arm 45 to move the link 43 down, rocking the bell crank 36 on its pivot 37 and straightening the various toggles. When the weight 30 is provided on extensions 28 the closing of the press is further facilitated. The amount of movement of the hand lever 47, link 43 and bell crank 36 is relatively small, while the amount of movement imparted to the toggles 32—33, 21—22, 12—14, and head lever L is relatively great, so that although a relatively light effort is required to establish the press in closed position, a relatively great pressure is created or obtained when the press is closed.

In Fig. 4, I have shown substantially the same construction and arrangement of parts as shown in Figs. 1-3, with the exception of the inclusion of a foot lever also connected to the link 43 so that either the hand lever or the foot lever, or both, may be operated selectively or collectively to close the press. In Fig. 4 the reference characters designate the same parts as in Figs. 1-3, with the following exceptions: Instead of providing a separate bell-crank 36, I provide a foot lever designated generally by the numeral 50 having a treadle 51 and an upstanding arm 52 connected at 53 to the link 43, said connection 53 corresponding to the connection 42 of Figs. 1-3. The foot lever has preferably formed as a part thereof what corresponds to the bell-crank 36, namely, a short horizontal arm 54 and a downwardly inclined long arm 55. The foot pedal 50 is pivoted adjacent the front of the frame 55 corresponding to the pin or shaft 57 of Figs. 1-3.

Obviously, under the construction of Fig. 4 either the hand lever 47 or the foot lever 50 may be depressed to effect closing of the press by straightening of the toggles, or the operator may use both his hand and foot on the hand lever 47 and foot lever 50, respectively, to effect closing of the press, since the link 43 is connected between and to both the hand lever and foot lever, and the pivot 53 is located on the short arm 54 to effect rocking of the portion 54—55 of the foot lever on pivot 56, the same as the link 43 of Fig. 1 effects rocking of the bell-crank 36 on its pivot 37.

It will be noted that in Fig. 4 I have shown the weight 31 omitted. This is an optional arrangement as the weight may be included or omitted under both forms of the invention, namely, the constructions of Figs. 1-3, and that of Fig. 4.

I claim:

1. In a pressing machine including a frame, a pair of pressing elements, a head lever on said frame carrying one of said elements, a plurality of operatively connected toggles one of which is operatively connected to the head lever to move it and said one element relative to the other, a bell-crank pivotally mounted on the frame and having one arm operatively connected to another of said toggles, a hand lever pivotally mounted on the frame adjacent the upper front portion thereof, said hand lever having a relatively long arm ex-

tending outwardly thru the front of the frame convenient to the hand of the operator, and a link connecting the other arms of the hand lever and bell-crank.

2. In a pressing machine including a frame, a pair of pressing elements, a head lever on said frame carrying one of said elements, a plurality of operatively connected toggles one of which is operatively connected to the head lever to move it and said one element relative to the other, a bell-crank pivotally mounted on the frame and having one arm operatively connected to another of said toggles, a hand lever pivotally mounted on the frame adjacent the upper front portion thereof, said hand lever having a relatively long arm extending outwardly thru the front of the frame convenient to the hand of the operator, said hand lever having its inner end curved into substantially hook-shape with the pivotal connection located intermediate the long arm and a relatively short arm provided on said hook-shape end, and a link connecting the said short arm of the hand lever and the other arm of the bell-crank.

3. In a pressing machine including a frame, a pair of pressing elements, a head lever on said frame carrying one of said elements, a primary toggle device consisting of interpivoted links, one of which is operatively connected to the head lever to move it and the said one element relatively to the other, and the other of which links is connected to the frame, a second toggle device consisting of interpivoted links, one of which is pivoted to one of the links of the primary toggle device, and the other of which is pivoted to the main frame, and a third toggle device consisting of inter-pivoted links, one of which is pivoted jointly with the pivotal means between the links of the secondary toggle device, and the other of which links is connected to the frame, a bell crank lever pivotally carried on the frame, together with a pivoted link which connects one arm thereof with the pivotal means which joins the links of the third toggle device, and means projecting outwardly through the front of the frame and convenient to the operator for rocking said bell crank lever and communicating motion to the toggle devices and their linkage.

4. In a pressing machine including a frame, a pair of pressing elements, a head lever on said frame carrying one of said elements, a primary toggle device consisting of interpivoted links, one of which is operatively connected to the head lever to move it and the said one element relatively to the other, and the other of which links is connected to the frame, a second toggle device consisting of interpivoted links, one of which is pivoted to one of the links of the primary toggle device, and the other of which is pivoted to the main frame, and a third toggle device consisting of interpivoted links, one of which is pivoted jointly with the pivotal means between the links of the secondary toggle device, and the other of which links is connected to the frame, a bell crank lever pivotally carried on the frame together with a pivoted link which connects one arm thereof with the pivotal means which joins the links of the third toggle device, and said bell crank having an integral extension projecting outwardly through the front of the frame with its end portion forming a pedal convenient to the foot of the operator.

THOMAS YOSYK.
